I claim the ornamental design for a firefighting tool, as shown and described.

DESCRIPTION

FIG. 1 is a rear perspective view of a firefighting tool, showing my new design;

FIG. 2 is a right-side elevational view thereof, the left-side elevational view being a mirror image thereof;

FIG. 3 is a top plan view thereof;

FIG. 4 is a bottom plan view thereof;

FIG. 5 is a rear elevational view thereof; and,

FIG. 6 is a front elevational view thereof.

The broken lines showing a handle in FIG. 1 depict environmental matter and form no part of the claimed design.
